UNITED STATES PATENT OFFICE.

EDWARD M. WEST, OF BRIDGETON, NEW JERSEY, ASSIGNOR, BY DIRECT AND MESNE ASSIGNMENTS, TO AUTOMATIC HAND-TRUCK COMPANY, OF BRIDGETON, NEW JERSEY, A CORPORATION OF NEW JERSEY.

TRUCK.

990,936.

Specification of Letters Patent.

Patented May 2, 1911.

Application filed April 29, 1910. Serial No. 558,500.

To all whom it may concern:

Be it known that I, EDWARD M. WEST, a citizen of the United States of America, and a resident of Bridgeton, in the county of 5 Cumberland and State of New Jersey, have invented certain new and useful Improvements in Trucks, of which the following is a specification.

This invention relates to trucks designed 10 to carry shipping boxes and packages of merchandise and is particularly useful in loading and unloading, and in transporting such goods.

My truck is more particularly designed to 15 lift and carry two or more shipping packages of the "hamper" type, although its usefulness is not limited to this type alone.

It is further designed to be loaded without the necessity of first lifting such boxes 20 on to the base of the truck, such loading with my truck being accomplished by the person at the back of the truck through the means hereinafter described.

My invention in its preferable embodiment, is shown in the accompanying drawings in which—

Figure 1 is a perspective view of the truck in position for loading; Fig. 2 is a vertical section on the line 2—2, Fig. 1; Fig. 3 is a 30 detail perspective view of the grappling hooks and their connections.

Referring to the drawings by numerals, 1 indicates the stringers of the frame of a wheeled truck of ordinary type and 2, 3 and 35 4 the cross bars or braces.

At the lower or forward extremity of the truck I secure the curved band 5 secured to the stringers of the truck by rearwardly extending arms 5^a. At points intermediate 40 the cross bars of the truck frame I also secure similarly curved bands 6 and 7. The curve or contour of these bands is designed to correspond substantially to the contour of the hamper basket or other rounded package 45 to be handled.

Secured preferably to the upper sides of the two upper cross bars are rock shafts 8 and 9 which in practice extend along the cross bars from one of the stringers of the 50 truck frame to approximately the middle of the bars and are provided at their centrally located ends with forwardly extending grappling hooks or claws 10. These

rock shafts are journaled on the cross bars by any suitable means, staples being shown 55 in the drawings as a simple and effective means to accomplish this result.

The ends of the rock shafts adjacent the stringer are provided with forwardly extending arms 11, the outer ends of which are 60 secured to coiled springs 12. These springs have their other ends preferably secured to the stringer of the truck and tend to rock the shafts 8 and 9 to pull their hooks 10 forwardly and downwardly. A rod 13 connects the two arms 11 near their inner ends 65 and causes the two rock shafts to operate in unison.

To allow for "lost motion" between the two rock shafts so that they may adapt 70 themselves to any difference in the relative positions of the tops of the crates, I form the lower end of the rod 13 with a slotted portion 14, whose slot is adapted to receive a bolt or pin 15, on the arm 11 of rock shaft 75 8. I preferably form this slotted portion by bending the end of the rod backward upon itself. I also prefer to secure to the underside of the cross bar 3 on which the rock arm 11 is located, a plate 16, the edge 80 of which projects somewhat beyond the outer face of said bar for the purpose hereinafter described. It will be obvious now that the person operating the truck, can, by raising or pulling upwardly on either one 85 of the hooks of the rock shafts simultaneously retract both of these hooks against the tension of the springs. To load, for instance, two superposed crates of the "hamper" type, on the truck, the person handling 90 the truck brings it up against two such crates with the frame elevated to a vertical position and the lower curved band 5 resting against the lower part of the bottom crate. The operator then draws the grappling hooks back against the tension of the springs and tilts the truck forward until these hooks are above the top of their respective crates when said hooks are released and are drawn by the springs downwardly 100 to grip the tops of the crates, the grappling hooks being in practice spaced to bear such relation to the standard size of crate.

"Hamper" crates of standard type are tapering and are provided with a hoop at 105 the top against the underside of which the

plate 16 is designed to bear when the truck is tilted to bring this plate against the bottom hamper basket. The crates being tapering, the lower one is held securely 5 wedged against the curved band 5 and both crates by reason of such engagement and because they are held against the truck and its supplemental curved bands 6 and 7 by the grappling hooks, can now be carried on the 10 truck with the latter in any position suiting the convenience of the operator. It will also be seen that my truck is practically "self loading" and that the crates to be carried thereby, do not have to be lifted up 15 and placed on the truck by hand but that the loading is all done by the operator and from the rear.

While I have described my truck as being especially designed to handle crates of the 20 "hamper" type, it is obvious that it can be used for carrying various other packages of the same general nature, such as kegs, etc.

What I claim as my invention is:—

1. A truck provided with a plurality of 25 grappling members spaced apart lengthwise of the truck and engageable with a plurality of superposed packages, and means for actuating said grappling members to effect such engagement.

30 2. A truck provided with a plurality of movable grappling hooks spaced apart lengthwise of the truck to engage with different superposed packages, spring actuated means for moving said grappling hooks to 35 effect such engagement, and means at the end of the truck for engaging with and supporting the lowermost of said superposed packages.

30 3. A truck provided with a plurality of 40 operatively connected grappling members spaced apart and engageable with each of a plurality of superposed packages, means for actuating said grappling members to effect such engagement, and supporting means at 45 the end of said truck engaging with the lowermost of said packages.

4. A truck provided with a plurality of rock shafts spaced apart lengthwise of the truck and provided with grappling members 50 engageable with a plurality of superposed packages.

5. Means for supporting and carrying a plurality of superposed packages comprising a wheeled truck, a plurality of spaced 55 rock shafts mounted thereon, grappling members connected to said rock shafts and movable thereby to engage with each of a plurality of superposed packages, and supporting means at the end of said truck engaging with the lowermost of said superposed packages.

6. A truck provided with a plurality of pivoted grappling members spaced apart lengthwise of the truck and engageable with 65 each of a plurality of superposed packages,

spring actuated means for moving said grappling members to effect such engagement and means at the end of the truck engaging with and supporting the lowermost of said superposed packages. 70

7. A truck provided with a plurality of rock shafts spaced apart and provided with grappling hooks engageable with each of a plurality of superposed packages, means at the end of said truck for supporting the 75 lowermost of said superposed packages, and means for simultaneously rocking said shafts to bring said hooks in package engaging position.

8. A truck provided with a plurality of 80 rock shafts spaced apart and provided with grappling hooks, a curved band at the base or end of said truck, supplemental curved bands intermediate its ends and means for rocking said shafts to actuate said 85 grappling hooks.

9. Means for supporting and carrying a plurality of superposed packages, comprising a wheeled truck, a plurality of rock shafts mounted on the frame thereof and 90 spaced apart, grappling hooks connected to said rock shafts and engageable with each of said superposed packages, a curved band at the end or base of said truck engageable with the side of the lowermost of said packages to support the same, connections between said rock shafts, and means for simultaneously rocking said shafts to bring said hooks into package engaging position. 95

10. Means for supporting and carrying 100 a plurality of superposed packages comprising a wheeled truck, spaced rock shafts mounted in the framing of said truck and provided with grappling hooks, arms formed at the ends of said shafts, a rod connecting 105 said arms, a curved band at the end or base of said truck engageable with the side of the lowermost of said superposed packages and spring means for simultaneously rocking said shafts to engage said hooks 110 with each of the superposed packages.

11. Means for supporting and carrying a tapering shipping package comprising a wheeled truck, a rock shaft journaled in the framing thereof and provided with a grappling hook, means for rocking said shaft to engage with the top of said package, a plate projecting from the truck framing and engaging the side of the package adjacent its top, and a curved band at the base or 120 end of said truck engaging the side of said package adjacent its bottom, substantially as described.

12. Means for supporting and carrying pairs of superposed tapering packages comprising a wheeled truck, a band at the base or end of said truck engaging the side of the lowermost package above its base, spaced grappling members mounted on the framing 125 of the truck and engageable with each of 130

said superposed packages, and means for actuating said members to effect such engagement.

13. Means for supporting and carrying 5 pairs of superposed tapering packages comprising a wheeled truck, a band at the base or end of said truck engaging and partially inclosing the side of the lower-most package above its base, a plurality of spaced rock 10 shafts mounted on the truck frame, and provided with grappling members, and means for rocking said shafts to move said grappling members into engagement with each of said superposed packages.

15 14. A truck for carrying a plurality of superposed packages provided with grappling members mounted on the truck frame and spaced lengthwise thereof distances corresponding substantially to the depth of 20 the packages, and located intermediate the truck side frames for engagement with the tops of the packages.

15. A truck provided with a plurality of spaced grappling members, engageable with

a plurality of superposed packages, means 25 for actuating said grappling members and connections between said members permitting independent movement of said grappling members.

16. A truck having a plurality of spaced 30 rock shafts mounted thereon and provided with grappling hooks, means for rocking said shafts to actuate said hooks, and yielding connections between said rock shafts.

17. A truck having a pair of spaced rock 35 shafts mounted thereon and provided with grappling hooks, crank arms on said shafts, a rod connected at its ends to said crank arms, one of said ends being slotted and co-acting with a pin carried by a crank arm, 40 and springs connected to said crank arms and rocking said shafts.

Signed by me at Bridgeton, New Jersey.
